W. V. CUNNINGHAM
ATTORNEY

UNITED STATES PATENT OFFICE

CLARENCE E. COLEMAN, OF BUFFALO, NEW YORK, ASSIGNOR, BY MESNE ASSIGNMENTS, TO DU PONT RAYON COMPANY, OF NEW YORK, N. Y., A CORPORATION OF DELAWARE

LOCKING DEVICE FOR SPINNING-BUCKET COVERS

Application filed September 24, 1928. Serial No. 137,517.

This invention relates to a device for locking the cover upon a rotating receptacle and more particularly upon a bucket used for spinning rayon. Such buckets are mounted upon revolving spindles from which they are driven by suitable friction devices. The rayon coming from the spinning nozzle is formed on the interior of the bucket in the form of a cake, the necessary twist being imparted by the rotation of the bucket. The rayon passes to the interior of the bucket through an aperture in a cover secured on the bucket. In the past difficulty has been experienced in securing the cover so that it will not slip in a direction opposite to the direction of rotation. It has been customary to secure the cover to the bucket by means of a spring wire clip, but any metal which is suitable for forming such a clip and which would retain its spring action is subject to corrosion from contact with the various acids and solutions to which it would be subjected.

Therefore, it is the object of my invention to provide a device which will securely lock the cover to the bucket and which may be actuated either manually or automatically; and which furthermore is in such form that it can be readily manufactured of acid-resisting material such as aluminum or molded bakelite.

In the accompanying drawing, in which I have shown selected embodiments of my invention:

Figure 1 is a vertical section through a bucket showing a cover locked in place according to my invention.

Figure 2 is a fragmentary plan view on an enlarged scale of a portion of the device shown in Figure 1.

Figure 3 is a section on the line 3-3 of Figure 2.

Figure 4 is a view corresponding to Figure 2 and showing a different embodiment.

Figure 5 is a section on the line 5-5 of

Figure 4.

Figure 6 is another view corresponding to Figure 2 and showing a third embodiment of my invention.

Figure 7 is a section on the line 7-7 of

Figure 6.

Referring now to the drawing, the numeral 1 designates a spinning bucket of any suitable form and which is provided with an annular shoulder 2 upon which is received the cover 3, this cover having the central aperture 4 therein whereby the rayon may be passed into the bucket. What I now consider my preferred embodiment is shown in Figures 1, 2 and 3, and, referring thereto, it will be seen that I have provided a pair of locking devices 5 in the form of plates pivoted eccentrically to the cover at 6. The pivot may be formed in any suitable manner, but I prefer to have it in the form of a boss 7 integral with the cover and internally threaded to receive a screw 8, the head of which extends beyond the boss to retain the plate 5 thereon. The plate may be made circular in form and provided with a wedge-shaped edge 9 adapted to be received within a recess 10 in the bucket, this recess being shown herein in the form of an annular groove. A suitable finger piece 11 may be provided for manual operation of the plate.

In operation, the plate may be moved to the locking position shown in Figure 2 by hand or, if not, then the movement will occur automatically when the bucket is rotated. Centrifugal force will cause the plate to rotate upon its pivot until the edge 9 is firmly wedged into the correspondingly shaped recess in the bucket. It will be noted that the pivots 6 are so disposed that the plates 5 cannot rotate through 360° when the cover is in position. Therefore, the plate will always tend to move outwardly further and consequently the greater the speed of rotation, the more firmly will the device lock the cover to the bucket.

Referring now to Figures 4 and 5, I have shown therein a different embodiment, in which the pivot is in the form of a screw 12 having a bearing 13 thereon and threaded into the cover 3. The plate 14 is pivoted on the bearing 13 and retained thereon by the head of the screw 12. It will be noted that the plate in this embodiment may rotate through 360°, its edge and the groove 15 in the bucket being so formed as to permit this rotation.

In Figures 6 and 7 I have shown still another embodiment in which the boss 7' and screw 8' are employed, these corresponding to the boss 7 and screw 8 of Figures 1, 2 and 3. The locking plate 16 is pivoted on the boss 7' as a bearing and is provided with the wedge-shaped edge 9' co-acting with a correspondingly shaped groove 10' in the bucket. A finger piece 17 may be provided for manual operation. In this form the locking plate may rotate through 360° but the plate and groove are provided with the co-acting wedge-shaped members to aid in tightly holding the cover in place on the bucket.

It will be seen that all of the parts of my invention, including the pivot and the locking plate are of such form that they may be made of acid-resisting metal or material. I avoid entirely the use of springs or other parts which have to be made of a material which will corrode under the action of the acids to which my device is exposed.

The cover will be locked in place either by hand or automatically. If, through carelessness of an operator, the locking device is not actuated, nevertheless, before an excessive speed of rotation is reached the device will operate automatically and securely lock the cover in position. In the preferred form of Figures 1, 2 and 3 the locking force will increase as the speed of rotation increases, thus supplying locking force as it is needed.

While I have shown selected embodiments of my invention I am aware that those skilled in the art may make changes therein without departing from the scope of my invention and I do not intend to limit myself except by the appended claims.

I claim:

1. In combination, a spinning bucket having a cover thereon and a recess therein, a locking plate eccentrically pivoted on said cover adapted to be received in said recess and locked therein by the centrifugal force of the rotating bucket.

2. In combination, a spinning bucket having a cover thereon and a recess therein, a locking plate eccentrically pivoted on said cover adapted to be received in said recess and locked therein by the centrifugal force of the rotating bucket, said plate being so disposed in respect to the bucket that the bucket prevents the plate from making a complete revolution on its pivot.

3. In combination, a spinning bucket having a cover thereon and a recess therein, a locking plate eccentrically pivoted on said cover adapted to be received in said recess and locked therein by the centrifugal force of the rotating bucket, said plate having a wedge-shaped edge and said recess being shaped to co-act with said edge.

4. In combination, a spinning bucket having a cover thereon and a recess therein, a plurality of locking plates eccentrically piv-

oted on said cover adapted to be received in said recess and locked therein by the centrifugal force of the rotating bucket, each of said plates having a wedge-shaped edge and said recess being shaped to co-act with said edge, each of said plates being so disposed in respect to the bucket that the bucket prevents the plate from making a complete revolution on its pivot.

5. In combination, a spinning bucket having a cover thereon and a recess therein, a plurality of locking means, each of said locking means comprising a boss integral with said cover, a locking plate eccentrically mounted upon said boss, a screw threaded in said boss and retaining said plate thereon, a finger piece on said plate for manual operation thereof, and a wedge-shaped edge on said plate adapted to be received in said recess.

6. In combination, a spinning bucket having a cover thereon and a recess therein, a plurality of locking means, each of said locking means comprising a boss integral with said cover, a locking plate eccentrically pivoted upon said boss, a screw threaded in said boss and retaining said plate thereon, a finger piece on said plate for manual operation thereof, and a wedge-shaped edge on said plate adapted to be received in said recess, said plate being so disposed in respect to the bucket that the bucket prevents the plate from making a complete revolution on its pivot.

7. In combination, a spinning bucket having a cover thereon and a recess therein, a plurality of locking plates eccentrically pivoted on said cover adapted to be received in said recess and locked therein by the centrifugal force of the rotating bucket.

8. In combination, a spinning bucket having a cover thereon and a recess therein, a locking plate eccentrically pivoted on said cover adapted to be received in said recess and locked therein by the centrifugal force of the rotating bucket, and means on said plate whereby the plate may be manually moved.

9. In combination, a spinning bucket having a cover thereon and a recess therein, and a plurality of locking plates eccentrically pivoted on said cover adapted to be received in said recess and locked therein by the centrifugal force of the rotating bucket, said plates being so disposed in respect to the bucket that the bucket prevents the plates from making complete revolutions on their pivots.

10. In combination, a spinning bucket having a cover thereon and a recess therein, and a plurality of locking plates eccentrically pivoted on said cover adapted to be received in said recess and locked therein by the centrifugal force of the rotating bucket, said plates having wedge-shaped edges and said recess being shaped to co-act with said edges.

11. In combination, a spinning bucket having a cover thereon and a recess therein, a

locking plate eccentrically pivoted on said cover adapted to be received in said recess and locked therein by the centrifugal force of the rotating bucket, said plate being so disposed in respect to the bucket that the bucket prevents the plate from making a complete revolution on its pivot, and finger means on said plate.

12. In combination, a spinning bucket having a cover thereon and a recess therein, a plurality of locking plates eccentrically pivoted on said cover adapted to be received in said recess and locked therein by the centrifugal force of the rotating bucket, said plates being so disposed in respect to the bucket that the bucket prevents the plates from making complete revolutions on their pivots, and finger means on said plates.

In testimony whereof, I have affixed my
signature to this specification.

CLARENCE E. COLEMAN.
